[57] **CLAIM**

The ornamental design for a combined bottle and cap therefor, substantially as shown and described.

DESCRIPTION

FIG. 1 is a perspective view of a combined bottle and cap therefor showing our new design;

FIG. 2 is a front elevational view thereof;

FIG. 3 is a side elevational view, the opposite side being substantially a mirror image thereof;

FIG. 4 is a back elevational view thereof;

FIG. 5 is a top plan view thereof;

FIG. 6 is a bottom plan view thereof;

FIG. 7 is a perspective view of a combined bottle and cap therefor showing a further embodiment of our new design;

FIG. 8 is a front elevational view of the embodiment shown in FIG. 7;

FIG. 9 is a side elevational view of the embodiment shown in FIG. 7, the opposite being substantially a mirror image thereof;

FIG. 10 is a back elevational view of the embodiment shown in FIG. 7; and

FIG. 11 is a top plan view of the embodiment shown in FIG. 7, the bottom plan view being substantially the same as shown in FIG. 5.
